UNITED STATES PATENT OFFICE.

WILLIAM A. DUDLEY SHORT, OF LEXINGTON, KENTUCKY.

STAFF HOOP-POUCH FOR HIGH-SPEED-TRAIN STAFF SYSTEMS.

SPECIFICATION forming part of Letters Patent No. 795,070, dated July 18, 1905.

Application filed April 28, 1905. Serial No. 257,845.

To all whom it may concern:

Be it known that I, WILLIAM A. DUDLEY SHORT, a citizen of the United States, and a resident of Lexington, in the State of Kentucky, have invented certain new and useful Improvements in Staff Hoop-Pouch for High-Speed-Train Staff Systems, of which the following is a specification, accompanied by drawings.

10 This invention relates to staff hoop-pouches for high-speed-train staff systems in which the staff and pouch are received by moving trains either from suitable cranes placed adjacent the track at suitable locations or from 15 persons on the ground. The staff and pouch are delivered to the cranes or catchers along the track by devices on the engines.

20 This improved staff hoop-pouch is designed to facilitate the handling and delivery of the staff to trains at high speed and is used in connection with what are termed "high-speed staff instruments."

25 The invention is an improvement over the usual staff hand-pouch which is used to deliver the staffs to trains; and it consists of a rubber pouch with a receptacle for carrying the staff in place.

30 Further objects of this invention will hereinafter appear; and to these ends the invention consists of a staff hoop-pouch for carrying out the above objects embodying the features of construction, combinations of elements having the general mode of operation, substantially as hereinafter fully described 35 and claimed in this specification and shown in the accompanying drawings, in which—

40 Figure 1 is a plan view with the hoop disconnected. Fig. 2 is a plan view with the hoop connected. Fig. 3 is an edge view of a modification. Fig. 4 is a detail view.

45 According to this invention the staff hoop-pouch consists of a hoop A, made of suitable flexible material, preferably rubber or rubber hose, the ends of which may be connected and disconnected. The hoop is also provided with suitable means, shown in this instance as a receptacle B, for carrying the whole or a portion of the staff. The receptacle B is preferably made of a piece of hose or other suitable material of larger diameter than the hoop

55 A and suitably secured to one end of the hoop, as by means of the rivets C. Preferably an aperture or slot D is provided in the side of the receptacle B in order to ascertain if the staff is in place when delivered to the train.

60 Suitable means are provided for securing the ends of the hoop together. As shown, the free end is provided with a ring E, preferably of brass, suitably secured thereto to act as a guard, and a transverse hole F is provided in the end adapted to register with the transverse hole G at the open end of the receptacle or connecting member B. A suitable cotter-pin may be thrust through said holes when the end of the hoop is inserted in the 65 open end of the receptacle B to hold the ends together.

70 In Fig. 3 the brass ring E is placed a little farther from the extreme end of the hoop, so that there is only room in the receptacle for a half-staff when the ends of the hoop are to be connected.

75 This improved staff hoop-pouch is more easily received by trainmen or by catchers placed on the train than those heretofore devised, because the hoop is received over the arm, which permits a certain amount of leeway or inaccuracy in catching the hoop and enables the staff to be delivered to trains at high speed.

80 Obviously some features of this invention may be used without others, and the invention may be embodied in widely-varying forms.

85 Therefore, without enumerating equivalents, I claim, and desire to obtain by Letters Patent, the following:

1. A high-speed-train staff apparatus comprising a flexible hoop and a uniting member for the ends of the hoop forming a receptacle for the staff.

90 2. A high-speed-train staff apparatus comprising a flexible hoop and a uniting hollow member for the ends of the hoop forming a receptacle for the staff, the ends of the hoop being thrust into said member.

95 3. A high-speed-train staff apparatus comprising a flexible hoop and a uniting hollow member forming a receptacle for the staff, said member being fixed to one end of the hoop and the other member of the hoop being

adapted to be removably secured to said member.

4. A high-speed-train staff apparatus comprising a flexible hoop and a uniting hollow member forming a receptacle for the staff, said member being fixed to one end of the hoop and having an opening in its side to enable the staff to be seen.

In testimony whereof I have signed this specification in the presence of two subscribing witnesses.

W. A. DUDLEY SHORT.
